UNITED STATES PATENT OFFICE.

LEVI K. FULLER, OF BRATTLEBOROUGH, VERMONT, ASSIGNOR TO J. ESTEY & CO., OF SAME PLACE.

DESIGN FOR AN ORGAN-CASE.

Specification forming part of Design No. 6,677, dated May 27, 1873; application filed February 19, 1873.

To all whom it may concern:

Be it known that I, LEVI K. FULLER, of Brattleborough, in the county of Windham and State of Vermont, have invented a Design for an Organ-Case, and assigned to J. ESTEY & Co., of the same place, of which the following is a specification:

The nature of my design is fully represented in the accompanying drawing, to which reference is made.

Figure 1 is an end elevation of an organ-case constructed in accordance with my design, and Fig. 2 is a cross-section of the same on line $x x$ of Fig. 1.

My design consists in having the ends of an organ-case made with segments of polygonal columns, as represented at A B, projecting therefrom, and extending from the base to the top.

This figure imparts a pleasing and agreeable effect to the eye of the observer, in harmony with the general symmetry of the structure.

I claim as my invention—

The design for an organ-case, formed by the segmental polygonal columns A B at the ends of the case, substantially as shown and described.

In witness whereof I have hereunto signed my name in the presence of two subscribing witnesses.

LEVI K. FULLER.
